UNITED STATES PATENT OFFICE.

ARTHUR II. FOWLER, OF PHILADELPHIA, PENNSYLVANIA, ASSIGNOR TO THE FOWLER & WOLFE MANUFACTURING COMPANY, OF PENNSYLVANIA.

DESIGN FOR A RADIATOR.

SPECIFICATION forming part of Design No. 29,182, dated August 9, 1898.

Application filed June 30, 1898. Serial No. 684,884. Term of patent 14 years.

To all whom it may concern:

Be it known that I, ARTHUR II. FOWLER, of the city and county of Philadelphia, State of Pennsylvania, have invented and produced 5 a new and original Design for Radiators, of which the following is a specification.

The design is shown in the accompanying drawing, which is a perspective view of a radiator-section embodying my design with the 10 cross-tubes running transversely.

The design consists in the shape or conformation of the radiator-section, and consists of an outer tubular structure composed of tubes connected together at the corners and a series 15 of cross-connecting tubular portions between two opposite outer tubular portions.

In the drawing, A A B B are the outer tubular portions, united at the corners by heads or enlargements C, and E are the series of cross-connecting tubular portions between two opposite outer tubular portions. 20

Having now described my design for radiators, what I claim as new, and desire to secure by Letters Patent, is as follows:

The design for a radiator substantially as 25 herein described and shown.

In testimony of which invention I hereunto set my hand.

ARTHUR II. FOWLER.

Witnesses:

CHARLES R. FOWLER,
JOHN T. MACDONALD.
